HELMET

Sterling W. Shuttleworth, Knoxville, Tenn.

Application November 3, 1953, Serial No. 27,439

Term of patent 3½ years

(Cl. D3—13)

To all whom it may concern:

Be it known that I, Sterling W. Shuttleworth, a citizen of the United States of America, residing at Knoxville, in the county of Knox and State of Tennessee, have invented a new, original, and ornamental Design for a Helmet, of which the following is a specification, reference being had to the accompanying drawing, forming a part thereof, wherein:

Figure 1 is a top plan view of a helmet, showing my new design,

Figure 2 is a bottom plan view of the same,

Figure 3 is a view in front elevation of the same, and

Figure 4 is a side view of the same.

I claim:

The ornamental design for a helmet, as shown.
